NAME PLATE MOUNTING MEANS

Edmund F. Schweller, Dayton, Ohio, assignor to
General Motors Corporation, Dayton, Ohio, a
corporation of Delaware

Application March 30, 1946, Serial No. 658,563

1 Claim. (Cl. 40—20)

1

This invention relates to cabinet constructions and particularly to means for securing an element upon the wall of a cabinet.

In recent years refrigerator and other cabinets have been provided with metal exterior walls that have a layer or coating of vitreous enamel baked thereon. This provides a porcelain-like finish on the walls which is brittle, thereby rendering it difficult to fasten or secure name plates or other elements upon the wall without chipping or cracking the finish thereon. When screws or bolts are passed through openings in the enamel wall to secure the element thereto, they are often threaded so tight that the porcelain is chipped or cracked about the edge of the openings. The present invention is directed to a novel method of anchoring name plates or other elements upon porcelain coated metal walls without danger of chipping or cracking the porcelain.

An object of my invention is to provide a simplified, low cost and easily assembled structure for securing a name plate or the like element upon a cabinet wall.

Another object of my invention is to provide fastening means for a rigid fragile plate securing structure, which will engage the cabinet wall beyond the edge of an opening in the wall through which a part of the structure projects so as to prevent chipping of the porcelain coating on the wall and breakage of the name plate.

In carrying out the foregoing objects it is a still further and more specific object of my invention to provide a member for fastening a name plate or the like element to a metal cabinet wall which has integral portions bent over one another for tightly clamping the plate thereto with a predetermined force and which portions are extended through slots in the wall to provide anchoring means for the plate and its supporting member.

Further objects and advantages of the present invention will be apparent from the following description, reference being had to the accompanying drawings, wherein a preferred form of the present invention is clearly shown.

In the drawings:

Fig. 1 is a view of a sheet metal member from which the name plate supporting member of the present invention is formed;

Fig. 2 is a view of the member shown in Fig. 1 after it has been bent into a shape adapted to receive the name plate;

Fig. 3 is an end view of the bent member disclosed in Fig. 2;

Fig. 4 is a front view of a refrigerator cabinet

2

having a name plate secured thereto by a member such as is disclosed in Fig. 2;

Fig. 5 is an enlarged fragmentary horizontal sectional view taken on the line 5—5 of Fig. 4, showing a name plate and its supporting member secured to a wall of the cabinet;

Fig. 6 is a fragmentary vertical sectional view taken on the line 6—6 of Fig. 5; and

Fig. 7 is a fragmentary sectional view taken on the line 7—7 of Fig. 5 with the wall insulation removed showing a securing spring clip.

Referring to the drawings, for illustrating the present invention, I have shown in Fig. 1 thereof a flat piece of sheet metal 10 having portions 11, 12 and 13 cut out as at 14 and 15 adjacent the cut-out portions. The edges of the long sides of the rectangular metal member 10 are bent to provide a pair of opposed flanges 16 extending outwardly from one face of member 10 and the connecting or integral portions 14 and 15 of the member are folded or bent as shown in Fig. 3 of the drawings. By folding the portions 14 and 15 as shown a substantially V-shaped portion 17 extends outwardly from the other face of member 10 for a purpose to be presently described. The member 10 formed as described provides a supporting element for a name plate or the like adapted to be attached to a wall of a cabinet.

In Fig. 4 of the drawings, I have shown a refrigerating apparatus of the household type including a cabinet generally represented by the reference character 20. Cabinet 20 includes insulated walls surrounding a food storage chamber therein and a door 21 providing access to the chamber, forms one of these walls. Both the cabinet 20 and door 21 have sheet metal exterior walls covering insulating material 23 disposed behind these walls and which walls have their outer surface coated with a vitreous enamel or porcelain substance. The outer metal wall 22 of door 21 is provided with a pair of elongated slots 24 (see Figs. 5 and 6) adapted to receive the V-shaped portion 17 after this portion has been further bent as will now be described. A name plate or the like element 27 is placed between the opposed flanges 16 on member 10 and then the fold 17 is closed, to draw the edges of the cut-out portions 11, 12 and 13 toward one another and to bring both wall parts of the portions 14 and 15 into abutting relation, for clamping the flanges 16 tightly against plate 27 and to provide the double walled projections indicated at 26 in Figs. 5, 6 and 7 of the drawings. Plate 27 may be formed of glass or any other suitable rigid fragile

material and may have any desired insignia cut or formed therein. The projections 26 are inserted or extended into the slots 24 double walled in wall 22. The closing of V-shaped portion 17 on member 10 to form the double walled projections 26 (see Figs. 5, 6 and 7) provides a substantially fixed distance or dimension between the opposed flanges 16 so as to maintain the plate 27 in assembled relation upon its supporting member 10 with a predetermined clamping force. Thereafter bowed spring clip means 29 are wedged between the wall 22 and the projections 26 to lock the member 10 upon the wall. Each rectangular spring clip 29 includes legs 31 (see Figs. 5 and 7) which bear against the inner surface of wall 22. Each clip 29 is also cut out to receive the double walled projections 26 and two edges of the cut-out portion are formed into a V-shape. Clips 29 are slit adjacent the cut-out portions thereof as at 32 to permit the edges of the V-shaped ears 33 to springingly grip both walls of the double walled projections 26. By wedging a clip 29 between wall 22 and the projections 26 the member 10 and consequently plate 27 are rigidly locked upon the wall 22. Legs 31 of clips 29 swingingly bear against the wall at points remote from the edge of the slots 24 in wall 22 and therefore no rigid tightening pressure or force is applied to the edges of the slots 24. Member 10 may be plated with any suitable substance such, for example, as chromium or the like for increasing the reflecting quality thereof so as to enhance the appearance of the insignia or name incorporated in the glass or plastic plate 27.

It will be apparent that I have provided an effective low cost fastening arrangement for anchoring a name plate or the like to a porcelain coated metal wall which can be quickly applied to the wall without danger of chipping or cracking the enamel thereon. In the present arrangement the sheet metal member, in addition to carrying the name plate, also provides the anchoring projections which extend through the wall. In this manner I have reduced to a minimum the number of parts required to secure a plate to a wall.

While the form of embodiment of the inven-

tion as hereindisclosed, constitutes a preferred form, it is to be understood that other forms might be adopted, as may come within the scope of the claim which follows.

5 What is claimed is as follows:

In combination, a wall having a slot therein, a rigid plate, means for mounting the plate upon said wall, said means comprising a substantially non-resilient sheet metal member having outwardly and forward extending opposed flanges bent toward each other, the rigid plate being disposed between said flanges on said member, said sheet metal member also having a rearwardly extending integral portion intermediate said opposed flanges, said integral portion of said member being reversely bent providing a double walled projection for insertion into the slot in said wall, the double walls of said projection being brought into and being maintained in abutment with one another due to its substantial non-resiliency to provide a fixed dimension between said flanges and being of substantially the same width as said slot for clamping said rigid plate to said member with a predetermined clamping force and for permitting said insertion without disturbing the abutting relation of walls of said projection, and a separate spring clip wedged between said wall and a portion of said projection extended through the slot therein for locking the sheet metal member to the wall.

EDMUND F. SCHWELLER.
